UNITED STATES PATENT OFFICE.

FRANK H. GATHERCOAL, OF WILMETTE, ILLINOIS.

GAME.

1,284,308.

Specification of Letters Patent. Patented Nov. 12, 1918.

Application filed January 19, 1918. Serial No. 212,589.

To all whom it may concern:

Be it known that I, FRANK H. GATHERCOAL, a citizen of the United States, residing at Wilmette, in the county of Cook and State of Illinois, have invented new and useful Improvements in Games, of which the following is a full, clear, concise, and exact description, reference being had to the accompanying drawing, forming a part 10 of this specification.

My invention relates to improvements in games and has for its object the production of a device by means of which a number of games may be played with one board and the 15 men and pins necessary therefor are always attached to the game board.

A further object is the production of a device of cheap and simple construction.

These and such other objects as may hereinafter appear are attained by my device, an embodiment of which is illustrated in the accompanying drawing, in which—

Figure 1 represents a front view of my device;

Fig. 2 is a rear view of my device; and

Fig. 3 is a perspective view of the pins and checkers used in the game.

Like numerals of reference indicate like parts in the several figures of the drawing.

Referring now to the drawing, 4 represents the game board, one side of which is divided off into a plurality of squares 5, making it in effect a checker board. On the opposite side of the board a number of holes 6 are formed whereby a number of games may be played by the use of pins 7. Checkers 8 are used in playing the games on the front face of the board. Near the edge of the board, preferably at one corner, is an 40 opening 9, through which is passed a string 10 secured to one of the lower corners of a receptacle 11, preferably of cloth in the form of a bag. The draw-string 13 passes through a hem 12 in the top of the bag 45 making it possible to close the opening and prevent the escape of the pins and checkers contained therein.

My device is especially applicable for use

in army camps and is of convenient size to fit within the pockets of the soldiers and 50 the fact that the pins are in a sense removably secured to the board renders it impossible for them to be lost. Of course, other forms of receptacles and methods of securing same to the board may be utilized, but 55 this would come within the scope of my invention.

It will be observed that the flexible draw-string 13 is in the form of a closed loop and that this loop, when the mouth of the bag 60 is closed, is just long enough to engage over the corner of the board diagonally opposite to the corner in which the hole 9 for the anchoring cord is placed, thereby utilizing the draw-string as a means of clamping the 65 bag against one face of the board and preventing the bag dangling about and becoming open.

Having thus described my invention, what I claim as new and desire to secure by Letters Patent is:—

1. A device of the class described, comprising a game board, one side being ruled into squares and adapted for the playing of certain games, movable pieces adapted to be 75 used in connection with the said squares, a plurality of holes passing part way through the opposite side, pins adapted to fit within said holes, a receptacle swingingly attached to said board and adapted to contain said 80 movable pieces, and means for closing the mouth of said receptacle.

2. A game board rectangular in shape, a bag for the reception of the game pieces to be used with the board, a device anchoring 85 the bag to one corner of the board, and a closed-loop draw-string for the mouth of the bag, this string loop being adapted to engage over the corner of the board diagonally opposite to the point of attachment of 90 the bag to the board to thus clamp the bag against one face of the board and hold the bag closed.

In witness whereof I have hereunto subscribed my name.

FRANK H. GATHERCOAL.
